Primary Examiner—T. Chase Nelson*Assistant Examiner*—Karen Acker*(74) Attorney, Agent, or Firm*—Scott B. Markow**CLAIM**

The ornamental design for a drill, as shown and described.

DESCRIPTION

FIG. 1 is a left, front, and top perspective view of a drill showing my new design.

FIG. 2 is a right side view thereof.

FIG. 3 is a left side view thereof.

FIG. 4 is a top view thereof.

FIG. 5 is a bottom view thereof.

FIG. 6 is a front view thereof; and,

FIG. 7 is a rear view thereof.

The broken lines and areas within the broken lines illustrate environmental structure that is not part of the claim. The broken lines and structure they depict form no part of the claimed design.

1 Claim, 5 Drawing Sheets
